United States Patent Office

Des. 197,030
Patented Dec. 3, 1963

197,030

BOTTLE

Arnold I. Lorenzen, Toledo, Ohio, assignor to Owens-Illinois Glass Company, Toledo, Ohio, a corporation of Ohio

Filed Mar. 27, 1963, Ser. No. 74,164

Term of patent 14 years

(Cl. D58—8)

FIG. 1

The side not shown is the same as the side shown.

The dominant features of my design reside in the portions shown in full lines.

I claim:

The ornamental design for a bottle, substantially as shown and described.
